UNITED STATES PATENT OFFICE.

ABNER DOBLE, OF DETROIT, MICHIGAN, ASSIGNOR TO GENERAL ENGINEERING COMPANY, OF DETROIT, MICHIGAN, A CORPORATION OF MICHIGAN.

METHOD OF IGNITING LIQUID FUEL.

1,260,523.

Specification of Letters Patent. Patented Mar. 26, 1913.

Application filed May 12, 1917. Serial No. 168,300.

To all whom it may concern:

Be it known that I, ABNER DOBLE, a citizen of the United States of America, and resident of Detroit, Wayne county, Michigan, have invented a certain new and useful Improvement in Methods of Igniting Liquid Fuel, of which the following is a specification.

My invention relates to the art of burning heavy hydrocarbons which are non-volatile or substantially so at normal temperatures, and my invention concerns a method of instantaneous ignition or initiation of combustion of such hydrocarbons in their normal temperature condition.

My invention has its application in connection with the utilization of heavy hydrocarbons, such as kerosene and distillate, as fuel for the rapid generation of steam in the power plant of steam-driven automobiles, wherein the elimination of the annoyance and delay of pre-vaporization of the fuel and the rapid generation of steam are essential requisites in a commercial successful automobile.

Heavy liquid hydrocarbons, such as kerosene, can, as I have found in practice, be very effectively and completely burned, without pre-heating or pre-vaporization, from an initially normal or so-called "cold" temperature condition and extremely high temperatures obtained for the generation of steam, by the atomization process of finely dividing or pulverizing the liquid and mixing it with proper amount of air to support combustion and confining the combustion in a closed refractory chamber which attains an intense incandescent temperature. The hydrocarbon at normal temperatures may be atomized or broken up and mixed with the proper proportion of air to complete combustion within said chamber, or the air which supports combustion may be used as the atomizing agency for finely dividing the hydrocarbon and projecting it into the combustion chamber. In any event, however, there must be a sufficient proportion of air in the mixture to complete combustion in the combustion chamber, without any smoke or soot whatever else the very advantage attendant upon a utilization of the atomizing method in a steam-driven automobile power plant, is lost. As before mentioned, I have found in practice that a mixture of the atomized fuel and air burned in a chamber in the

manner above mentioned can be completely consumed without soot and smoke, but such a mixture (which I will refer to for convenience as the main or completely combustible mixture), has a relatively excessive proportion of air and a relatively small proportion of atomized fuel. In other words, relatively speaking, this mixture is rich in air and lean in hydrocarbon.

The extreme desirability in an automobile power plant, of instantaneous initiation of combustion of fuel, and the use of an electric spark for this purpose, is at once obvious, but a mixture such as I have just described will not ignite at normal temperature by means of an electric spark, although, after having been properly ignited, it will sustain complete combustion in said chamber. So far as I am able to ascertain, the failure of this mixture to ignite from a spark is due to the fact that a spark of practical proportions, although intensely hot, is comparatively small in volume, and in such a relatively lean mixture the particles of fuel are separated in a comparatively large volume of air to such an extent that the air absorbs the heat and prevents the transmission of heat to adjacent particles from those ignited. Furthermore, if in addition the body of mixture is moving at comparatively high velocity, the particles do not remain in the small zone of heat of the spark long enough to become ignited.

I have discovered, however, that a mixture of finely divided hydrocarbon and air at the normal atmospheric temperatures can readily be instantly ignited by an electric spark if the mixture is excessive or rich in hydrocarbon and lean in air, but on the other hand, a mixture of this character is not completely combustible, there being insufficient air therein to entirely or completely consume the hydrocarbon even under the most favorable conditions, hence such a mixture (which for convenience of reference I will term the auxiliary or incompletely combustible mixture) is not adapted for continuous combustion purposes because it burns incompletely, is productive of smoke and soot, disagreeable odor and does not develop the temperature necessary in an automobile power plant. As before mentioned, however, this mixture will readily and repeatedly ignite by an electric spark because, so far as I am able to ascertain, the particles

of hydrocarbon are relatively close together and not diluted with air to any great extent, hence the heat generated by the spark, although small in volume, is readily dissipated and absorbed into the fuel particles instead of air, and the particles in the immediate heat zone ignite and readily transmit their flame to the adjacent particles, thus instantly building up a body of flame throughout the mixture. Now, by utilizing the characteristics of both of these mixtures, I am able to bring about, without pre-vaporization, the instantaneous ignition of a completely combustible mixture at normal temperature for the sustained or continued production of heat, by means of an electric spark, which result, in the case of an automobile power plant, leaves nothing for the operator to do but to start the sparking and mixture forming mechanisms, and which in practice amounts to nothing more than the operation of an electric switch.

I accomplish these results by producing a rich mixture by atomizing hydrocarbon and air, igniting the same by a spark, then producing a mixture sufficiently rich in air to bring about complete combustion, the latter mixture being ignited by the flame of the first mixture.

The fuel ignition and burning apparatus which I disclose in the accompanying drawings illustrates the preferred manner in which my improved method is carried into effect in a steam-driven automobile power plant.

In these drawings—

Figure 1 is an end view of double Venturi fuel atomizing structure for carrying out my improved method, part of this structure being sectioned to illustrate the relation of the main fuel nozzles and Venturi passages.

Fig. 2 is an end view, from within the combustion chamber, of the main Venturi tubes and auxiliary chamber.

Fig. 3 is a vertical sectional view, substantially on the line 3—3 of Fig. 1.

Fig. 4 is a similar section substantially on the line 4—4 of Fig. 1.

The main or completely combustible mixture, to which I have referred, is in the present structure produced by a blower A and Venturi atomizers B of which there are two placed side by side, although for the purposes of my invention one atomizer is sufficient. The two atomizers in this case produce two streams or currents of mixture. These atomizers are formed by the tubular Venturi passages formed in the casting or member C, and the nozzles D for the liquid fuel. The Venturi passages are tapered, being larger in diameter at their inner discharge ends, and the fuel nozzles D are positioned in the throats thereof in upright relation, their ends reaching to about the center of the Venturi throats. The blower A

is mounted at the ends of the atomizer passages with its outlet A' directly connected with the said passages, the blower outlet being divided into two passages to register with the two Venturi passages. The blower may, of course, be of any suitable type for the purpose, but preferably is of the so-called volume type consisting of a casing and a fan or blade wheel rotatable therein, and capable of moving a large constant volume of air. It is preferably driven by a small electric motor A¹, one terminal of which is connected by the conductor E with a source of current such as an electric battery F. The other terminals of both battery and motor are grounded. A switch G is provided in this circuit by which the operator may control the operation of the motor as desired. The blower provides a constant blast or current of air through each of the Venturi passages, which in accordance with the principles of atomization draws the liquid fuel from the nozzles and pulverizes or finely divides and mixes with the fuel, thus producing a spray of mixture from each of the nozzles which is projected from said atomizers. In this structure the mixture thus produced is projected into a closed combustion chamber G, the walls of which are formed of refractory material capable of being rendered incandescent by the heat of combustion. This chamber has side walls G' and a bottom wall G², and the corners and angles are well rounded so as to give the combustion a general bowl shape. The Venturi member extends substantially horizontally in position to project the main mixture into said chamber, and when the mixture is ignited two flames sweep across the combustion chamber to the opposite wall thereof, where they meet with a curved baffle (not shown) by which the streams are deflected or turned back horizontally upon themselves, thus producing a violent swirling of the flame within the chamber. The flames are confined by the walls and bottom of the chamber which with great rapidity become highly incandescent and thus create an intense uniform zone of heat within the chamber, which brings about a complete combustion of the hydrocarbon. The atomizer and blower are so proportioned that the main mixture from these atomizers is supplied with copious quantities of air from the blower, sufficient to support the complete combustion of the fuel within the chamber. In consequence, the mixture is relatively dilute and cannot be directly ignited from the small volume of flame from an electric spark. I therefore produce the auxiliary mixture which will ignite by the spark and effect the ignition of the main mixture by the flame of the ignited auxiliary mixture. In the structure shown, a long chamber J is formed in the member C and positioned un-

derneath and between the main Venturi passages. This chamber is closed except at its inner end, part of the walls of the end portions of the main Venturi passages being cut 5 away to provide direct communication between the auxiliary chamber and the Venturi passages at their inner discharge ends. In addition, the structure has an upturned lip K across the ends of the Venturi passages 10 and the auxiliary chamber so as to divert or deflect the auxiliary flame upwardly directly in the path of the main mixture projected from the nozzles whereby to immediately ignite said mixture. At the closed end of the auxiliary chamber there is 15 a fuel nozzle L fed from the same source of hydrocarbon at the same normal temperature as the main nozzles being connected with the same manifold L' which is positioned and fastened on the under side of the member C. Adjacent this fuel nozzle L, in fact formed in the same member, is an air passage L² having its upper end L³ positioned at an angle to the end of 20 the nozzle passage L, so as to form an air nozzle in atomizing relation to the fuel nozzle L. The air nozzle is connected with a source of compressed air, such as an air tank (not shown) under a few pounds 25 pressure, and when the air is flowing the fuel is drawn from nozzle L and atomizes or finely divides it, projecting the mixture through the auxiliary chamber to the inner end thereof. A relatively small proportion 30 of air is thus mixed with the pulverized fuel but just enough to support combustion to some extent, the mixture being very rich in fuel and in such condition that it will readily ignite with a spark. This mixture, rich 35 in fuel, fills the chamber and provides a very fertile zone or field for the heat of the spark to ignite and accelerate combustion in the mixture. The fuel and mixture are of course at normal, that is, atmospheric tem- 40 perature. The spark in the structure shown is produced at the terminals N of the plug N', which terminals are positioned directly in the path of the spray of rich cold mixture from the auxiliary atomizer. Having 45 thus initiated combustion in the auxiliary mixture, which in practice is instantaneous, a flame of substantial proportions is produced which is emitted from the inner end of the auxiliary chamber J into the path of 50 the main mixture and ignites the main mixture as before described. The duration of the auxiliary flame need be but momentary because in practice, the matter of time from the initiation of the spark until the main 55 streams of mixture become ignited is practically instantaneous. However, the volume of auxiliary mixture is relatively smaller than the volume of main mixture and does not, when ignited, produce any appreciable 60 volume of smoke, hence if it is continued for

any length of time the smoke is not noticeable, particularly since the smoke is carried into the combustion chamber by the main mixture and there consumed. The electrical equipment for the production of the 70 spark may be of any suitable type for the purpose. In the drawings I illustrate an ordinary spark coil, the secondary winding S of which is connected with the spark plug in a grounded circuit S', while the primary 75 winding P is in a grounded circuit P' which includes the battery F. This circuit also includes the suitable switch G by which the operator may control the spark as and when desired. The combustion chamber is in 80 practice closed at its upper end by a steam generator R, the lower ends of the evaporating units of which are indicated, so that the heat produced by the main flame of burning fuel is instantly available for the generation 85 of steam.

The apparatus herein disclosed for carrying out my improved method constitutes subject-matter of my co-pending application Serial No. 168,301, filed May 12, 1917. 90

I claim:—

1. The method of initiating combustion in a mixture at normal temperature of finely divided liquid hydrocarbon and air of such proportion of air as to insure complete combustion of said fuel, which consists in first igniting by means of an electric spark an incompletely combustible mixture rich in hydrocarbon, and causing the flame of said rich mixture to initiate the combustion of 95 said completely combustible mixture.

2. The method of initiating combustion in a spray of normally cold mixture of finely divided heavy hydrocarbon and sufficient air to support complete combustion of said 105 mixture, consisting in maintaining a zone of said mixture, momentarily maintaining in igniting relation to said mixture a second mixture of said finely divided hydrocarbon and insufficient air to support complete combustion, and initiating combustion in said incompletely combustible mixture at normal 110 temperature by means of an electric spark.

3. The method of igniting heavy hydrocarbons which are non-volatile or substantially non-volatile at normal temperatures, which consists in maintaining a spray of rich mixture of air and said hydrocarbon in atomized but incompletely combustible condition, igniting said mixture by means 120 of an electric spark to establish a flame, maintaining a mixture of said atomized hydrocarbon and sufficient air to completely combust said hydrocarbon, and directing the flame of said spark ignited flame into said 125 completely combustible mixture.

4. The method herein described of igniting heavy hydrocarbon oils while cold, consisting of maintaining a main blast of com- 130 minuted hydrocarbon highly diluted with

- air to a sufficient degree to insure complete combustion of the hydrocarbon, maintaining adjacent thereto an auxiliary blast of air commingled with an excess of comminuted hydrocarbon, igniting said auxiliary richer blast by an electric spark, and directing the flame of the burning auxiliary blast into the main blast to thereby ignite the same.
- 10 5. The method of igniting heavy hydrocarbons which are non-volatile or substantially non-volatile at normal temperatures, which consists in maintaining a spray of rich mixture of air and said hydrocarbon 15 in atomized but incompletely combustible condition, igniting said mixture by means of an electric spark to establish a flame, maintaining a mixture of said atomized hydrocarbon and sufficient air to completely 20 combust said hydrocarbon, directing the flame of said spark ignited flame into said completely combustible mixture, and causing said combustible mixture so ignited to sweep over and circulate about a broad ex- 25 panse of a material adapted to become highly incandescent thereby insuring complete combustion.
6. The method of initiating combustion in a mixture of sprayed kerosene and air incapable at normal temperature of ignition 30 by an electric spark, which consists in igniting by means of an electric spark a mixture of sprayed kerosene and air at normal temperature capable of ignition by said spark, and igniting said first mixture by the flame 35 of said spark-ignited mixture.
7. The method of initiating combustion in a mixture of sprayed non-volatile hydrocarbon and air incapable at normal temperature of ignition by an electric spark, 40 which consists in igniting by means of an electric spark a mixture of said sprayed non-volatile hydrocarbon and air at normal temperature capable of ignition by said spark, and igniting said first mixture by 45 the flame of said spark-ignited mixture.

Signed by me at Detroit, Mich., this 3d day of May, 1917.

ABNER DOBLE.
